CUTTING HEAD ASSEMBLY

Edward G. McGovern, Baltimore, Md.

Application December 17, 1953, Serial No. 398,799

11 Claims. (Cl. 51—34)

1

This invention relates in general to improvements in metal working tools, and more specifically to an improved cutting head assembly for a cut-off grinder.

It is to be understood that under given conditions, a certain grinding wheel will cut only at a certain effective rate. Any attempt to vary the conditions under which the grinding wheel operates will reduce its effectiveness. Therefore, a cutting head assembly is generally limited in production by the effective rate of cutting of the grinding wheel carried thereby.

The primary object of this invention is to provide an improved cutting head assembly which is so constructed whereby the cutting rate thereof may be substantially double that of conventional cutting head assemblies.

Another object of this invention is to provide an improved cutting head assembly which utilizes a pair of grinding wheels, the grinding wheels being mounted to operate sequentially on metal being cut or ground with the grinding wheels operating at different depths.

A further object of this invention is to provide an improved cutting head assembly for reciprocating grinders, the cutting head assembly including a pair of aligned grinding wheels with the grinding wheels being set to grind at different depths so that a pair of cuts may be made in a single traversing of the cutting head assembly.

A still further object of this invention is to provide an improved cutting head assembly which includes means for mounting a pair of grinding wheels for operation in unison, the means being adapted to position the grinding wheels so that they have different effective depths of cuts and being so constructed whereby the relationships of the wheels shift at the end of each effective stroke of the cutting head assembly.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of a reciprocating grinder utilizing the cutting head assembly which is the subject of this invention, a support for material to be worked on being omitted;

Figure 2 is a fragmentary front elevational view of the reciprocating grinder of Figure 1 and shows the general relationship of the cutting head assembly with respect to a supporting trackway;

2

Figure 3 is an enlarged rear perspective view of the cutting head assembly and shows the general details thereof, a hood portion thereof being omitted for purposes of clarity;

5 Figure 4 is an enlarged fragmentary vertical sectional view taken substantially upon the plane indicated by the section line 4—4 of Figure 1 and shows the general relationship of the grinding wheels with respect to the supporting carriage therefor;

10 Figure 5 is an enlarged fragmentary bottom plan view of the cutting head assembly and showing the relationship of the grinding wheels and the means for driving the same;

15 Figure 6 is an enlarged fragmentary transverse vertical sectional view taken substantially upon the plane indicated by the section line 6—6 of Figure 4 and shows the manner in which a support arm for the grinding wheels is rockingly carried by a support for limited movement; and

20 Figure 7 is an enlarged fragmentary perspective view of the lower end of the support and shows the relationship between the support and the support arm rockingly carried thereby, and the means for limiting rocking movement of the support arm, means for rocking the support arm relative to the support being omitted for purposes of clarity.

25 Referring now to the drawings in detail, it will be seen that there is illustrated in Figures 1 and 2 a reciprocating grinder utilizing the cutting head assembly which is the subject of this invention. The reciprocating grinder includes an elongated platform 10 which extends transversely of a work carrying platform (not shown) and is mounted for vertical movement on a pair of plungers 12. The plungers 12 are parts of vertically extending fluid cylinders 14 whose operations are controlled by electrically controlled valve means (not shown).

30 The cutting head assembly, which is the subject of this invention, is referred to in general by the reference numeral 16 and includes a carriage which is referred to in general by the reference numeral 18. The carriage 18 is formed of a platform 20 and supporting rollers 22. The supporting rollers 22 are guidingly engaged with rails 24 mounted on the platform 10 in spaced parallel relation. Secured to the platform 20 is a plunger 26 of a horizontally disposed fluid cylinder 28. The fluid cylinder 28 is provided with a control valve (not shown) which is remotely electrically controlled.

35 Carried adjacent each of the fluid cylinders 14 in offset relation with respect to the platform 10

is a standard 30. The standard 30 has mounted on the upper end thereof a limit control switch 32. Each limit control switch 32 is alternately engaged by a lever 34. There are two such levers 34, with each lever 34 being disposed adjacent an end of an elongated shaft 36 which is rigidly secured to the platform 20 by mounting arms 38. It will be understood that the levers 34 are adjustably mounted on the shaft 36 to vary the relationship of the carriage 18 with respect to the platform 10 when the limit switches 32 are tripped.

It is to be understood that the above mentioned parts are portions of a conventional reciprocating grinder, and their relationship need not be set forth in more detail herein. It is also to be understood that normally a single grinding wheel is carried by the platform 20 of the carriage 18 and it is to be driven. In operation, the carriage 18 is reciprocated back and forth along the tracks 24 due to the actuation of the hydraulic cylinder 28. As the carriage 18 reaches the end of one of its strokes, one of the levers 34 will trip the limit switch 32 with which it cooperates. The tripping of the limit switch 32 will result in the reversal of flow of fluid in the cylinder 28 to reverse the movement of the carriage 18. Simultaneously, fluid will be permitted to escape from the cylinders 14 so as to permit the lowering of the carriage 18 and its associated grinding wheel a predetermined amount so that the grinding wheel may be lowered into position for a next cut.

It will be noted that the platform 10 is provided with an elongated opening 40 between the rails 24. The opening 40 has received therein an intermediate portion of an elongated support 42 carried in depending relation by the underside of the platform 20 of the carriage 18. The support 42 is bifurcated at its lower end, as best illustrated in Figure 7, and includes a pair of depending flanges 44 which are inwardly offset. Passing between the flanges 44 and supported for rocking movement is a support arm 46.

Referring now to Figure 6 in particular, it will be seen that the support arm 46 is mounted for rocking movement relative to the support 42 on a shaft 48 which extends transversely of the support arm 46. The shaft 48 includes a generally rectangular cross-sectional central portion 50 which is rigidly keyed to the support arm 46. The shaft 48 also includes circular cross-sectional end portions 52 which are suitably journaled in the flanges 44. The end portions 52 are provided with keyways in which are seated keys 54. The keys 54 retain collars 56 on the shaft 48.

It will be noted that each of the collars 56 is provided at its top with a notch 58. Received in the notch 58 of each collar is a depending keystone-shaped lug 60 carried by the support 42 and disposed outwardly of an adjacent flange 44. It will be understood that the relationship between the lug 60 and the notch 58 is such so as to limit the rocking movement of the support arm 46 with respect to the support 42.

Carried by the support arm 46 adjacent opposite ends thereof and extending transversely of the support arm from opposite faces thereof are tubular shaft housings 62. Mounted in each of the shaft housings 62 and extending through the support arm 46 is a rotatable shaft 64. Carried by one of each rotatable shaft 64 is a gang pulley 66. Carried by the opposite end of each shaft 64 is a grinding wheel 68. It will be noted

that the gang pulleys 66 and the grinding wheels 68 are in respective alignment.

Carried by the platform 20 of the carriage 18 and pivotally connected thereto at one edge is a mounting plate 70. The mounting plate 70 has the opposite edge thereof supported by adjustable jack elements 72. Carried by the mounting plate 70 is an electric motor 74. The electric motor 74 has an armature shaft 76 on which is mounted a gang pulley 78. The gang pulley 78 is in the same plane as the gang pulleys 66. Entrained over the gang pulleys 66 and 78 is a plurality of drive belts 80. It will be understood that the mounting plate 70 is pivoted with respect to the platform 20 to vary the tension in the drive belts 80 so as to permit effective driving of the shaft 64 by the electric motor 74.

Secured to the underside of the platform 20 and extending in opposite directions therefrom are water supply lines 82. The water supply lines 82 have reversely bent end portions 84 which terminate in spray nozzles 86 directed at the grinding wheels 68. The flow of a coolant or other suitable liquid through the supply pipe 82 to the spray nozzles 86 is controlled by a valve 88.

Referring now to Figure 4 in particular, it will be seen that mounted on and supported by the supply pipes 82 is a hood 90. The hood 90 is secured to the supply pipes 82 through the use of suitable clips 92. It is understood that the hood 90 is to protect workmen against any flying cuttings or portions of the grinding wheels 68.

Extending transversely between portions of the hood 90 and disposed in overlying relation with respect to each spray nozzle 86 is a strap 94. The strap 94 has secured to the underside thereof in supporting relation a pair of shields 96. The shields 96 are in the form of plates which converge towards an associated grinding wheel 68.

It is understood that the grinding wheels 68 lie in the same plane so that when the cutting head assembly 16 is reciprocated transversely of an object to be cut, the grinding wheels 68 follow in the same path. It is to be understood that if the grinding wheels 68 were disposed in the same vertical plane, that only the lead one of the grinding wheels would have a grinding action during its travel across the object being ground or cut. In order to permit the effective operation of the cutting head assembly 16, it is necessary that the trailing one of the grinding wheels 68 be set for a deeper cut than the lead grinding wheel. Further, inasmuch as the relationship of the grinding wheels 68 reverses at the end of each stroke of the cutting head assembly 16, it is necessary that the particular relationship of the heights of the grinding wheel 68 be reversed accordingly.

In order to retain the grinding wheels 68 in proper relation, there is carried within the lower portion of the support 42 an electromagnetic device which is referred to in general by the reference numeral 100. The electromagnetic device 100 includes a pair of contacts 102 mounted on opposite sides of the support 42. Also, the support arm 46 is provided with a pair of L-shaped contacts 104 with each contact 104 being disposed adjacent a contact 102 of the electromagnetic device 100. The electromagnetic device 100 is connected to the limit switches 32 for actuation thereby. The relationship between the limit switches 32 and the electromagnetic device 100 is such that when the cutting head assembly 16 moves to the right, as viewed in Figure 4, the right contact 102 is energized to draw the asso-

ciated contact 104 thereto. This pivots the support arm 46 in a counter-clockwise direction and lowers the left hand grinding wheel 68 while the right hand grinding wheel 68 is elevated. It will be understood that the difference in the respective heights of the grinding wheels 68 is equal to the effective cut of one of the grinding wheels. Thus, as the cutting head assembly 16 is moved to the right, as viewed in Figure 4, the cutting wheel 68 disposed at the right will make an initial cut across the material to be cut. Then, the left hand cutting wheel 68 will follow in its track and make a second cut. Thus, it will be seen that the cutting head assembly 16 is of such a nature whereby twice the effective cut may be obtained through a single reciprocation of the cutting head assembly, and thereby, the efficiency of a reciprocating grinder provided with the cutting head assembly 16 is substantially doubled.

When the cutting head assembly 16 reaches the right end of its stroke, the associated limit switch 32 is tripped to effect movement thereof to the left. The limit switch 32 also reverses the supply of current to the electromagnetic device 100 with the result that the right hand contact 102 is no longer energized, and the left hand contact 102 is energized. This causes a tilting of the support arm 46 in a clockwise direction to reverse the relationship of the two grinding wheels 68. It is to be understood that the rocking of the support arm 46 is accomplished at the end of each stroke of the cutting head assembly 16.

In view of the foregoing, it will be seen that there has been devised an extremely simple cutting head assembly, which, through the utilization of two grinding wheels which are selectively positioned during the operation of the reciprocating grinder of which the cutting head assembly is a part, will produce two cuts on material to be cut. Inasmuch as the cuts are disposed in superimposed relation, it will be seen that the effectiveness of the stroke of the cutting head assembly will be doubled. While it is realized that a slightly longer time will be required for an effective stroke of the cutting head assembly, it is to be understood that the time is not materially increased, and therefore, the production of a reciprocating grinder provided with the cutting head assembly which is the subject of this invention will be substantially doubled. It is also to be understood that although the cutting head assembly has been illustrated as being in the form of a cut-off head, it may be utilized in conventional grinding operations.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set rela-

tive to the other so that both cut-off wheels may have effective grinding depths.

2. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set relative to the other so that both cut-off wheels may have effective grinding depths, means carried by said support for selectively rocking said support arms in sequence with reversing of the direction of travel of said carriage.

3. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set relative to the other so that both cut-off wheels may have effective grinding depths, means carried by said support selectively retaining said support arm in a rocked position.

4. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set relative to the other so that both cut-off wheels may have effective grinding depths, means carried by said support for selectively rocking said support arms in sequence with reversing of the direction of travel of said carriage, said means being in the form of an electromagnetic device, cooperating contacts carried by said support arm on opposite sides of said support.

5. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set relative to the other so that both cut-off wheels may have effective grinding depths, a power unit carried by said carriage drivingly connected to said cut-off wheels.

6. A cutting head for a reciprocating cut-off grinder comprising a carriage, a depending support carried by said carriage, a support bar carried by said support, aligned cut-off wheels rotatably carried by said support bar at opposite ends thereof, said support bar being rockably mounted relative to said support whereby one of said cut-off wheels may be selectively set relative to the other so that both cut-off wheels may have effective grinding depths, a power unit carried by said carriage drivingly connected to said cut-off wheels, said power unit being mounted on a mounting plate, said power unit being connected to said cut-off wheels by flexible drive belts, said mounting plate being pivotally mounted for tensioning of said drive belts.

7. A cutting head for a reciprocating cut-off grinder comprising a carriage, a depending support carried by said carriage, a support bar carried by said support, aligned cut-off wheels rotat-

ably carried by said support bar at opposite ends thereof, said support bar being rockably mounted relative to said support whereby one of said cut-off wheels may be selectively set relative to the other so that both cut-off wheels may have effective grinding depths, cooperating means on said support and said support arm for limiting rocking of said support arm.

8. For use in combination with a carriage reciprocatingly mounted on a track and controlled by limit switches, a cutting head comprising a support adapted to be carried by the carriage, a support arm rockably carried by said support, cut-off wheels rotatably carried by said support arm at opposite ends thereof, means carried by said support selectively rocking said support arm and retaining said support arm in a rocked position, said means being operatively controlled by the limit switches.

9. For use in combination with a carriage reciprocatingly mounted on a track and controlled by limit switches, a cutting head comprising a support adapted to be carried by the carriage, a support arm rockably carried by said support, cut-off wheels rotatably carried by said support arm at opposite ends thereof, means carried by said support selectively rocking said support arm and retaining said support arm in a rocked position, said means being operatively controlled by the limit switches, cooperating 20

means on said support and said support arm for limiting rocking of said support arm.

10. For use in combination with a carriage reciprocatingly mounted on a track and controlled by limit switches, a cutting head comprising a support adapted to be carried by the carriage, a support arm rockably carried by said support, cut-off wheels rotatably carried by said support arm at opposite ends thereof, means carried by said support selectively rocking said support arm and retaining said support arm in a rocked position, said means being operatively controlled by the limit switches, said means including an electromagnetic device, cooperating contacts carried by said support arm.

11. For use in combination with a carriage reciprocatingly mounted on a track and controlled by limit switches, a cutting head comprising a support adapted to be carried by the carriage, a support arm rockably carried by said support, cut-off wheels rotatably carried by said support arm at opposite ends thereof, means carried by said support selectively rocking said support arm and retaining said support arm in a rocked position, said means being operatively controlled by the limit switches, said cut-off wheels being in alignment and intended to alternatingly follow in the path of each other.
